[57] CLAIM

The ornamental design for a combined container and cap, as shown and described.

DESCRIPTION

FIG. 1 is a top, front and right side perspective view of a combined container and cap showing my new design; FIG. 2 is a side elevation of the container shown without the cap for clarity of illustration, the opposite side is identical;

FIG. 3 is a top plan view of FIG. 2, the bottom is unornamented;

FIG. 4 is a front elevation of FIG. 2, the rear elevation is identical; and,

FIG. 5 is a perspective view of the combined container and cap shown with the cap separated from the container.

Fig. 1.

Fig. 5.
